1 Claim

ABSTRACT OF THE DISCLOSURE

A combination puzzle and educational game in which there is a mounting board formed of magnetically attractive material and puzzle elements each equipped with permanent magnets attractive to the board for removable attachment thereto, the puzzle elements comprising interfitting sections forming an object when properly interfitted together and each section bearing a portion of the word describing the object formed by the sections when properly interfitted together.

SUMMARY OF INVENTION

The principal object of my invention is not only to afford amusement by requiring a child to properly interfit the sections of the puzzle element together to form an object, but also to provide a medium of educating the child by associating a word with the object. The invention is advantageous over the prior art in that each section of the puzzle element has associated therewith a portion of the word which describes or identifies the object formed when the puzzle sections are properly interfitted together. The invention may employ objects of various shapes and designs and of different characters thereby to afford a wide range of objects and words for the amusement and education of the child.

The invention will be best understood by reference to the accompanying drawings showing the preferred form of construction, and in which:

FIG. 1 is a plan view of the invention;

FIG. 2 is a plan view of the puzzle sections shown in exploded relation with respect to each other;

FIG. 3 is a sectional detail view taken substantially on line 3—3 of FIG. 1;

FIG. 4 is a plan view of the invention showing a different puzzle character from that shown in FIG. 1.

While I have shown in the drawings of this application the character or the object of the puzzle element as being in the form of a house and also in the form of a dog, it is to be understood that the puzzle element may take a wide range of characters, such as animals, buildings, scenes, and the like.

To accomplish the several objects of the invention, I provide a mounting board 10 which is substantially flat and formed of magnetically attractive material such, for example, soft iron or the like.

The puzzle object is generally indicated at 11 and in the present instance comprises a plurality of sections 12, 13 and 14, which may be formed of any suitable material, such as plastic. The abutting edges 15 of such sections are irregular so as to add to the amusement and the skill of the child in placing the sections in proper interfitting relation with respect to each other upon the mounting board 10 so as to form the object 11.

Formed along corresponding edges on each section 12, 13 and 14, are integral extensions 16 forming

2

alphabetical letters which, when the sections 12, 13 and 14 are properly interfitted together, form a word which describes or identifies the object 11 thus produced by the interfitting sections. In the present instance, the object shown in FIG. 1 is a house and the letters of the sections 12, 13 and 14 form the word HOUSE.

By such arrangement the child is educated to associate the word thus spelled out, with the object formed by the interfitting sections.

In FIG. 4 of the drawings, the object there shown is in the form of a dog 17 which comprises a plurality of interfitting sections 18, 19 and 20, each integrally carrying an extension 21, 22 and 23 in the form of letters of the alphabet which, when the puzzle sections are properly interfitted, spell out the word DOG, thus identifying to the child the object formed by the interfitting sections.

In the preferred form of construction there is provided in the rear surface of each of the puzzle sections 12, 13 and 14, as well as 18, 19 and 20, a recess 24. Mounted in the recess 24 are permanent magnets 25 which are attracted to the board 10 for removably holding the puzzle sections in place when positioned upon the board 10.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A combination puzzle and educational toy comprising:

- (a) a relatively flat mounting board formed of magnetically attractive material,
- (b) a plurality of puzzle sections adapted to form an object in relief on one surface of the mounting board,
- (c) each of said puzzle sections providing a preformed edge interconnectable with a corresponding edge of one of the other puzzle sections,
- (d) third dimensional extensions in the shape of alphabetical letters integrally formed out of one edge of each of said puzzle sections and positioned with respect to the preformed edge thereof so as to be equally spaced from each other to form a word designation for the object when said puzzle sections have their preformed edges interfitted, and
- (e) magnetic elements carried by each of said puzzle sections and attractive to the board for removably holding said sections upon the surface of said board.
